S. Rossman.
Paper Mach.

N° 19,045. Patented Jan. 5, 1858.

Fig. 2.

UNITED STATES PATENT OFFICE.

STEPHEN ROSSMAN, OF STUYVESANT, NEW YORK.

MACHINERY FOR MANUFACTURING PAPER.

Specification of Letters Patent No. 19,045, dated January 5, 1858.

To all whom it may concern:

Be it known that I, STEPHEN ROSSMAN, of Stuyvesant, in the county of Columbia and State of New York, have invented a new and useful Improvement in Machinery for Manufacturing Paper; and I do hereby declare that the following is a full, clear, and exact description of the same, reference being had to the accompanying drawings, forming part of this specification, in which—

Figure 1, is a sectional elevation of that part of the machinery used in the manufacture, known as the "second press." Fig. 15 2, is a plan of the same.

Similar letters of reference indicate corresponding parts in both figures.

The object of my improvement is to prevent the breaking or tearing of the paper, as 20 it passes from the upper one of the second press rolls to the drier.

My improvement consists in lifting the web of paper from the upper press roll by means of a lifting roller, arranged and operated substantially as hereinafter set forth. The slight adhesion of the web to this small roll eases it off the upper press roll and prevents it breaking, and if a slight break should occur in the web, it prevents the edge 25 of the break being carried under the edge of the doctor and the break being thereby enlarged. This improvement, though simple in its character, is highly important in its results and it is found by practice to effect 30 a great increase in the quantity of paper produced in a given time, by saving all or nearly all the time sacrificed by the breakages of the web that occur when it is not used.

40 To enable others skilled in the art to apply my invention, I will describe it with reference to the drawings.

A, is the framing of the machinery. B, is the lower press roll and C, is the upper 45 press roll. D, is the doctor. E, is the blanket. All these parts may be arranged and constructed in the usual manner.

F, is the lifting roll whose use constitutes my improvement. This roll may be 50 of wood, metal or other suitable material. It is represented as having its journals b, b, fitted to guides a, a, attached to the housings G, G, of the press rolls, and to be resting on the upper press roll, but instead of 55 being fitted to guides, the journals b, b, may rest in bearings similarly arranged to

the guides a, a, to keep the periphery of the roll F, at a short distance from that of the upper press roll C, without resting upon it. Motion is given to the said roll F, by gearing from the upper press roll or by other 60 convenient means to give its periphery the same velocity as the peripheries of the press rolls.

The web, the section of which is indicated 65 in Fig. 1, by a red line, is conducted by the blanket between the two press rolls and then, leaving the blanket, passes upward and returns over the top of the upper press roll, all in the usual manner and at the line 70 where it should leave the surface of the upper press roll it comes in contact with the surface of the roll F, and by its slight adhesion to the said surface is eased off the press roll.

75 It will be observed that the lifting roll F rotates in a contrary direction to the press roll C.

In ordinary paper machines, no lifting 80 roll like my roll F, is employed to lift the paper from the press roll C, but the paper passes from the periphery of said press roll in a straight line to the periphery of another roll, the shaft of which is on the same parallel line as the shaft of the "doctor" D. 85 The situation of this latter roller and also the line of movement of the web of paper from the periphery of the press roll C, is shown by the blue outlines in Fig. 1. It will be seen that the web of paper, under 90 this arrangement, has no support between the periphery of the press roll C, and the blue outline roller just mentioned; consequently the weight of the paper has a tendency to tear or break the web. This liability to break or tear is greatly increased 95 owing to the fact that the press roll C rotates in the same direction that the paper moves; and as there is a slight adhesion between the web of paper and the periphery of the roll C, the latter tends to pull down and carry 100 along with itself the web of paper. If the web of paper is not sufficiently strong to resist this tendency, it becomes torn or broken.

Much care, watchfulness, and labor is required on the part of the attendant to guide and unite the paper when thus broken. The frequency of the breaks causes much waste of paper. By the use of a lifting roll F, to disengage the web of paper from the roll C, 110 all the above difficulties are overcome. The roll F not only serves to lift the web from

the press roll C, but also as a support to the paper after leaving the roll. This is owing to the adhesion of the web to the roll F. The web falls from the roll F by its own gravity, as it moves along to the drying rollers.

I am aware that the use of guide rollers in various relations to the main cylinders is common in paper machinery. Examples are seen in the patents of G. W. Turner, Jan. 27, 1852, and D. G. Jones, Dec. 11, 1855. I make no claim to anything contained in those devices. But to the best of my knowledge and belief, it is new in the

manufacture of paper, to lift the web from the press roll, as I have described; and therefore

Having thus described my invention, what I claim as new and desire to secure by Letters Patent, is:

Lifting the web of paper from the upper press roll C, by means of a lifting roll F, arranged and operating substantially as herein set forth.

STEPHEN ROSSMAN.
